J. J. CAROW

METHOD OF ORNAMENTATION

Filed May 29, 1923

Patented Feb. 9, 1926.

1,572,348

UNITED STATES PATENT OFFICE.

JOHN J. CAROW, OF WASHINGTON, DISTRICT OF COLUMBIA.

METHOD OF ORNAMENTATION.

Application filed May 29, 1923. Serial No. 642,205.

To all whom it may concern:

Be it known that I, JOHN J. CAROW, a citizen of the United States, residing at Washington, in the District of Columbia, 5 have invented certain new and useful Improvements in Methods of Ornamentation, of which the following is a specification.

The invention has for an object to provide a method of ornamentation suitable 10 for use both in embellishment of surfaces and in forming screen elements to be viewed by transmitted light.

It is an aim to enable the production of distinctive designs without limitation, yet 15 permitting the production of several general types of configuration at will. Another object is to enable the production of various pleasing color designs in similar figure motifs, or widely different figure effects in 20 the same color scheme. Another aim is to present a method of forming small units from large ones, and for enabling a single pattern piece to be formed in a checker board pattern or appearance. Another aim 25 is to present a method of producing original and desirable designs without requiring artistic ability on the part of the artisan, but enabling the employment of persons after very short training, to carry out general 30 instructions of another competent to determine the proper selection and use of colors, and the mixing of mediums for carrying pigments or other color materials.

Additional objects, advantages and features of invention are involved, as may be understood from the following description and accompanying drawings, in which,

Figure 1 is a representation of one general character of design producible by my 40 method, using thin color medium,

Fig. 2 is a similar view of a modification of the effect in the first design, using thicker medium,

Fig. 3 is a view representing one stage of 45 the method,

Fig. 4 is a similar view showing a further stage,

Fig. 5 is a fragmentary view of two elements in course of ornamentation illustrating the manner of separating two elements 50 of glass in the execution of the process.

Fig. 6 is a cross section of an element ornamented by my method,

Fig. 7 is a similar view of an element 55 when intended for surface ornamentation.

Figure 8 is a fragmentary face view of a checker-board effect produced with my invention.

Figure 9 is a fragmentary cross section of a puzzle structure.

In my Patent #1,204,743, issued November 14th, 1916, there is illustrated a method and means for decoration which is applicable in part in carrying out my present invention, if desired. My present invention 60 may be utilized in making tile elements to be applied as indicated in the patent mentioned, as well as in many additional ways for which it is suitable.

In the main, my invention is utilized in 70 preparing elements for surface decoration using transparent glass as a carrying body for a decorative design applied to one side thereof. But it may be utilized for making an attractive pattern on glass for use as 75 a screen, without destroying its transparency, or obstructing the view therethrough only in part if desired. Also, the invention may be used for decorating the 80 surfaces of opaque objects by adaptation of the same method used on transparent materials.

In the simplest form of the invention, two pieces of glass, *a* and *b*, of the same size are taken and coated each with a similar paint *c*, or other color medium, the medium being either flowed on or applied with a brush; and the two pieces are then pressed together with their painted surfaces contacting. Care must be taken to 90 see that all air is expelled from between the coated surfaces. The pieces are adjusted with their edges alined, and next a knife or suitable wedge is entered between the plates at one corner, just sufficiently to start 95 the plates separating slowly. Here it should be stated that preferably the glass should be thin enough in proportion to its thickness, it is believed, to permit a slight bending thereof, which is permitted by the resilience of the glass so that a progressive separation occurs from the point of first separation. This may not be essential in 100 all instances however, and discretion may be exercised in this, governed by the character of pattern desired, and the effects which experience will show result from varying qualities in the carrying body as the glass or other material may be termed. As 105 the two plates separate, the wedge or knife 110

is turned or worked so as to further pry the plates apart, until they may finally be removed from contact with each other entirely.

5 In the initial operation, the edges are separated sufficiently to create a vacuous condition therebetween and to admit air, which at once begins to enter at irregularly spaced points between the coated surfaces. As the 10 elasticity of the plates causes a stress by which they tend to separate at their inner parts, the vacuous condition or suction extends further and further, the air entering along the edges being drawn inwardly toward the middles of the plates, and moving in stream fashion from the outer parts. In the separation of the plates the adhesion of the molecules of the liquid being greater than the cohesion between the liquid and 20 the glass the color coating is pressed aside by each little stream of air, until the coating on the glass is partly or entirely pressed away from the air paths, forming plant-like patterns extending inward from the edges of 25 the plates, somewhat similar design being formed on both plates, although they will be modified, according as one is faced down and the other up.

The character of the pattern will be affected by the speed with which the plates are separated, and also by the viscosity of the color medium. Thus, a thick and sticky medium will produce a pattern having small figures in the detail, while a thin medium will produce larger elements in the design. Also, slow separation is conducive to more complete simulation of plant growth, while rapid separation will produce a more varied effect having less continuity, and including 40 many dots and swirls. For the color applied to produce this pattern one is selected which may be covered with a contrasting color *d* to show the pattern against a suitable ground. Black may be used, to be finished 45 with a ground of white. Many different desirable effects may be produced with the same pattern color, by varying the color of the ground. Thus, when using white I have employed black, pink, blue, and other colors, 50 and also metal paints, including bronze and other powders, alternatively. Some of the patterns simulate the veining of marble and others suggest plant forms.

Large bodies may be figured in this way 55 and utilized as panels or otherwise integrally, or they may be cut into segments of desired forms and used as decoration. A very attractive checker-board effect may be produced (see Fig. 8), either as ornamentation solely, suitable for trays, walls and otherwise, or for actual employment as a checker-board. This is accomplished by taking a plate after forming the pattern thereon and cutting the patterned plate into 60 squares of equal size, and then coating them

alternately with two different ground colors *d*. By reassembling the pieces in their original relation, on a suitable support, a checker-board is provided of a unique appearance, having a continuous or homogeneous pattern 70 of veins or filigree extending throughout. If desired further, a border of different appearance may be formed by cutting therein segments of different shape from that of the checks and giving these a ground color 75 different from both those used on the checks.

The consistency of the color medium in some measure determines the degree of sharpness in the patterns formed in the 80 course of separation of the plates, but with a proper consistency, the design produced will have delicate gradations in part, and more or less sharp line in other parts if the speed of separation is properly governed. 85 Also, if, in the course of separation of the plates, a slight relative vibration is imparted to them, transversely to the mean plane between, a delicate ridging is produced in the gradations and following the 90 contours of the patterns. This vibration may be produced by oscillating the instrument used to separate the plates. A further variety may be attained by giving the plates a slight rotary movement relatively during 95 the process of separation. Also, by sifting dry pulverized pigment *h* of contrasting color upon the plates before or after application of the color in which the pattern is to be produced, and after the plates have 100 been pressed together, giving them a slight relative turn one way and then back, before separation, additional novel effects may be produced. The rotary movement should not ordinarily be over 5 or 10 degrees. 105

Instead of backing a plate with a ground color after the formation of a pattern, it may be coated with a transparent varnish *e*, and used as a light for windows, partitions or screens, and otherwise as may be desired. 110

Further, in case it is desired to grain or ornament a surface on an opaque body *g*, it may be given an initial ground color, or its own material utilized as the ground. The initial color being dried with a smooth surface, it is then covered with a medium suitable for forming the pattern, and a flexible metal plate, or a glass plate laid thereon which if desired may also be coated on its contacting surface with the same pattern 115 color. This plate is then separated from the body to be ornamented with the desired motion in accordance with the method already described, producing the pattern. This may then be covered with varnish *e* 120 or other protection (see Fig. 7).

It is also possible to form the pattern by rolling a large roller over the surfaces upon which a pattern is to be formed, the roller and the surfaces being first coated with a 125 130

color medium of proper consistency to cause the formation of the pattern by the separation of the roller surface from that of the ornamented body. Rollers of small diameter will produce small figured patterns, while rollers of large diameter will produce larger pattern details.

A very attractive puzzle may be formed by my method, by forming a pattern on a plate, and then cutting it into small segments to be matched so as to produce the original pattern. In the production of these, the plate would have a flexible and easily torn backing secured thereto, and a glass cutter employed to form the lines of cleavage, after which the plate is manipulated so as to cleave the parts without separation from the backing. They would then be held in position so that the purchaser or recipient could observe the complete design, after which the segments would be torn apart, and the reconstruction of the piece then attempted. If desired, a blueprint of the original pattern could be taken from the plate and supplied with the puzzle after separation of the segments, and this would obviate the necessity for the use of the flexible backing.

It is found that slow-drying paints assure the secure and permanent adhesion of the color medium to the glass, and therefore, while a moderate proportion of turpentine may be utilized in modulating the viscosity or consistency of the mediums, a liberal amount of linseed oil is also employed, without special driers.

In order to produce color blendings of multifarious character, it is possible to sift dry powdered pigments onto the medium for forming the pattern after it has been applied to the surface to be decorated, and in the pressing together of the plates and their subsequent separation the sifted color forms nuclei of various forms adding a pleasing variegation to the effect produced. By a proper selection of colors, designs appropriate to different color schemes may be produced as desired. The character of the backing coat on elements formed of trans-

parent glass also largely determines the effect, as to color harmony.

In the separation of the plates, the speed with which they are separated affects the quality of the design. As a rule it is desirable to effect the separation more slowly when thick paints are used than when thin mediums are employed. However, it is sometimes preferable to effect more rapid separation with a given medium than at other times. Thus, it is possible by rapid separation, employing a moderately thick medium, to cause a softening of the outlines and the formation of a slight film over the parts which would be clear when slow separation is employed.

The movement of the color medium in forming the patterns may be in part or wholly due to capillary attraction, though the tendency to the production of a vacuum between the plates as separated undoubtedly results in some effect by the pressure of the air.

After sifting of dry color thereon the movement of the color medium incident to separation of the plates or other surfaces results in the diffusion for limited distances of each small or large unit of the sifted color. The dry pigment powder may be applied otherwise than by sifting, the method being determined by the character of effect desired.

It may also be found desirable to use more than one color in the pattern forming medium or coating.

What is claimed:—

The method of forming a mosaic consisting in coating a body with a pattern color medium, applying another closely fitting body thereto and separating the two to cause a configuration of the color medium, then separating the body into segments, applying different ground colors to respective segments, then assembling the segments in their original relation to form a continuous surface.

In testimony whereof I have affixed my signature.

JOHN J. CAROW.
